Pittsburgh, Pa., a corporation of Pennsylvania

Application September 14, 1944, Serial No. 554,037

21 Claims. (Cl. 175—294)

1

My present invention relates to a carrier-current or other pilot-channel phase-angle-detecting relaying system, adapted to protect a section of a three-phase transmission-line against faults. My present system is an improvement over the system shown in an application of Mehring, Goldsborough and myself, Serial No. 534,846, filed May 10, 1944.

The Mehring et al. system has a theoretically possible defect, which might conceivably result in an incorrect blocking-operation on an internal B-C-to-ground fault, under system-conditions in which substantially all of the positive-sequence current comes from one end of the protected line-section, and substantially all of the zero-sequence current comes from the other end. This comes about by reason of the fact that the Mehring et al. system utilizes a derived current-responsive single-phase quantity, which is vectorially compounded of the properly weighted positive- and zero-sequence components of the line-current, to alternately produce a succession of local operating impulses during positive half-cycles of the locally derived line-current quantity, and to transmit, to the other line-terminal, a succession of restraining impulses during negative half-cycles of the locally derived line-current quantity.

An object of my present invention is to avoid the possibility of such a difficulty by utilizing only the positive-sequence component of the local line-current as the means for developing the alternating successions of operating and restraining impulses, in combination with an overvoltage relay-means which serves as a means for detecting the relative phase-angles between the two terminal line-currents of the protected section, by responding to the operating impulses when they are not effectively opposed by restraining impulses received from a distant line-terminal.

As the positive-sequence line-current component is not a reliable fault-detector, and as it is sometimes desirable to avoid the transmission of restraining impulses under normal fault-free line-operating conditions, a further object of my invention is to also provide a suitable multi-responsive fault-detector means, capable of detecting the existence of any one of a plurality of different kinds and phases of ground- and phase-faults, and to utilize said fault-detector means for supervising the operation of the phase-angle-detecting relay-means, as by causing the positive-sequence means to be effective only when there is a fault-indication by said fault-detector means.

A still further object of my present invention is to utilize a zero-sequence current- or voltage-

2

component, or other ground-fault detector-means, for increasing the effectiveness of the single-phase voltage which is derived in response to the positive-sequence component of the line-current. This provision makes it possible to obtain a ground-fault sensitivity of response, which approximates that of a two- or three-phase fault, notwithstanding the fact that the ground-fault may have a much smaller positive-sequence current-component.

This ground-fault-responsive sensitivity-increase of a positive-sequence line-current response is of general application, not limited to apparatus for comparing the current-directions or relative phase-angles at the two ends or terminals of the protected line-section. It is also particularly applicable to the control of a relay-tube.

A more generally expressed object of my invention is to provide a single relaying circuit which produces a uni-directional voltage of limited magnitude, in response to a detection of a predetermined ground-fault condition on the line, and adds such a voltage in series with another voltage-component which is in some manner responsive to the positive-sequence component of the line-current.

A still further object of my invention is to control a relay-tube or other polarity-responsive device, by causing it to be responsive to a pulsating voltage having a phase which is responsive substantially solely to the positive-sequence component of the line-current, and providing a uni-directional voltage of substantially non-pulsatory form, in the event of a predetermined ground-fault condition, for increasing the sensitivity of response to the pulsating voltage. Such ground-fault response is preferably so arranged that it will not by itself cause operation of the device.

A still further object of my invention is to utilize a single-phase control-voltage to cause two tubes to be alternately conductive on positive and negative half-cycles, respectively, and to provide a unidirectional voltage of substantially non-pulsatory form in a circuit of said tubes in a polarity facilitating the operative conductivity of said tubes.

With the foregoing and other objects in view, my invention consists in the circuits, systems, apparatus, combinations, parts, and methods, hereinafter described and claimed, and illustrated in the accompanying drawing, wherein:

Figure 1 is a diagrammatic view of circuits and apparatus illustrating an embodiment of my invention, and

Figs. 2 to 13 are curve-diagrams which will be referred to in the explanation of the invention.

In Fig. 1, I show the terminal equipment for only one terminal of a three-phase transmission line 14, which is connected to a bus 15 through a three-phase circuit-breaker 16. Only one terminal equipment is illustrated, because the equipments at the other line-terminal or terminals are, or may be, identical to the illustrated equipment. The circuit-breaker 16 is illustrated as having a trip-coil TC, and an auxiliary make-contact breaker-switch 16a.

The three-phase line-current is derived by means of a bank of line-current transformers 17, which respond to current-flow into the protected line-section, at the terminal in question. This three-phase line-current is fed into any suitable phase-sequence network or filter 18, which is provided with a zero-sequence or neutral-current terminal I_0 , a pair of positive-sequence terminals I_1 in which a single-phase voltage is produced, which is responsive substantially solely to the positive-sequence component of the line-current, and a pair of positive-plus-zero phase-sequence terminals I_{10} , in which a voltage is produced in response to the vectorial sum of the positive-sequence line-current, plus a constant times the zero-sequence line-current, as in the type HCB network which is shown in the Harder patent 2,183,646, granted December 19, 1939, and assigned to the Westinghouse Electric & Manufacturing Company.

The zero-sequence network-terminal I_0 is utilized to energize a saturating zero-sequence-responsive transformer T_0 , the primary winding of which is connected in the neutral circuit of the line-current transformers 17. The pairs of network-terminals I_1 and I_{10} are respectively utilized to energize a saturating positive-sequence transformer T_1 , and a saturating positive-plus-zero sequence-responsive transformer T_{10} .

Usually and preferably, but not necessarily, in accordance with my present invention, some, or preferably all, of the derived network-voltages are of limited magnitude, which may be accomplished by making some or all of the transformers T_1 , T_0 and T_{10} saturating. The secondary terminals of some or all of the transformers T_1 , T_0 and T_{10} , particularly the positive-sequence transformer T_1 , are also shunted by a voltage-limiting glow-tube 19, as described in the Harder patent.

The zero-sequence transformer T_0 is utilized to energize a load-resistor R_1 through a double-wave rectifier, such as the rectifier-bridge 20, so as to furnish a unidirectional current, having substantially no ripples, to said load-resistor R_1 . The ripples may be still further removed by a parallel-connected filter-capacitor FC1. The saturating nature of the zero-sequence transformer T_0 results in producing a unidirectional current of substantially limited magnitude, which is applied to the resistor R_1 , so as to produce a unidirectional voltage-drop of a roughly constant magnitude in the resistor R_1 , whenever there is a ground-fault on a transmission system. The negative terminal of the resistor R_1 is indicated at 21, and the positive terminal at 22.

The positive-plus-zero sequence-responsive transformer T_{10} is utilized to energize the operating coil of a fault-detector FD, which is intended to be representative of any multi-responsive fault-detector means, or any equivalent combination of fault-detector means, adapted to be responsive to a plurality of different kinds and phases of ground- and phase-faults on the three-

phase transmission-system. This fault-detector FD is utilized to detect the presence of any one of a number of different kinds of faults, preferably all different kinds and phases of faults, whether such faults occur within the confines of the protected line-section, or outside of said protected line-section.

According to my present invention, the positive-sequence-responsive transformer T_1 is utilized to produce a succession of substantially flat-topped "operating" voltage-impulses of substantially constant magnitude during the positive half-cycles of the positive-sequence line-current, and to produce a succession of substantially flat-topped "restraining" voltage-impulses of substantially constant magnitude in response to the negative half-cycles of the positive-sequence current-component. To this end, I preferably utilize the same means which is shown in the aforesaid Mehring et al. application, except that the means is responsive to a single-phase voltage, the phase of which is determined substantially solely by the positive-sequence component of the local line-current, instead of using the positive-plus-zero sequence-responsive network, as in said Mehring et al. application.

As shown in Fig. 1, I provide two gas triodes or other grid-controlled gas tubes G_1 and G_2 of a sustained-discharge type; that is, of a type in which the grid fires the tubes, or starts the discharge, but is unable to extinguish the tube or interrupt the discharge. The grids of these tubes G_1 and G_2 are connected to the respective secondary terminals 23 and 24 of the tube-controlling transformer, in this case the positive-sequence transformer T_1 . An intermediate voltage of the secondary transformer-circuit is derived from two serially connected resistors R_2 and R_3 , which are connected across the secondary terminals 23 and 24. The connecting-point 25 between these resistors is connected to a negative battery-terminal or bus (-), through a C-battery E_c , and the zero-sequence resistor R_1 , according to my invention. The C-battery E_c is so connected as to make the point 25 more negative than the negative battery-terminal (-), or, in general, so as to make the point 25 have a potential too negative, by a predetermined amount, to cause the tubes G_1 and G_2 to fire, under the impressed anode-cathode voltage-conditions. The polarity of the zero-sequence resistor R_1 is in opposition to that of the C-battery E_c .

The cathode-circuits 26 and 27 of the gas tubes G_1 and G_2 are connected to the negative battery-terminal (-) through cathode-resistors R_4 and R_5 , respectively. The anode-circuits 28 and 29 of the respective gas tubes G_1 and G_2 are respectively connected to plate-resistors R_6 and R_7 , the other terminals of which are connected to a common conductor 31 which is connected, through a make-contact 32 of the fault-detector FD, to the positive battery-terminal (+). The two anode-circuits 28 and 30 of the gas tubes G_1 and G_2 are joined by an interconnecting circuit containing a capacitor C_1 .

The two gas tubes G_1 and G_2 are thus connected in a so-called "trigger" circuit, which operates as follows: During positive-sequence line-current half-cycles of one polarity, which I shall call the negative half-cycles, or more specifically during the negative half-cycles of the derived current-responsive voltage of the positive-sequence saturating transformer T_1 , the secondary transformer-terminal 23 is positive. This

transformer-terminal 23 is also the grid-terminal of the gas tube G1. At an early stage in these negative half-cycles, the positive voltage of the secondary terminal 23 with respect to the intermediate secondary point 25, becomes more positive than the blocking bias of the C-battery Ec, or at least sufficiently positive to cause the first gas tube G1 to fire. It will be understood that the gas tubes have such characteristics that, when they are once fired, or when current is once started in their plate-cathode circuits, such plate-cathode current will continue to flow until the voltage applied across the plate and cathode terminals of the tube is reduced to zero or reversed, even for a moment.

At the beginning of the next half-cycle of the output-voltage of the positive-sequence transformer T1, which I shall call a positive half-cycle, the other secondary terminal 24 becomes positive with respect to the secondary intermediate point 25, and fires the second gas tube G2.

Before the firing of the second tube G2, the potential of its plate-circuit 30 was substantially the potential of the positive battery-terminal (+), assuming that the fault-detector contact 32 is closed, while the potential of the plate-circuit 29 of the first tube G1 was at a somewhat more negative value, due to the voltage-drop in the plate-resistor R6 of the first tube. When the second tube G2 fires, however, its plate-circuit 30 tends to drop to the same potential as the plate-circuit 29 of the first tube, but the voltage-charge on the interconnecting capacitor C1 causes the potential of the anode-circuit 28 of the first tube G1 to momentarily drop to a value which is more negative than the potential of the cathode circuit 26 of said first tube G1, thus extinguishing the first tube G1 in the moment required for the discharge of the interconnecting capacitor C1. In the next half-cycle, the first tube G1 fires again, and in turn extinguishes the second tube G2 by momentarily causing a negative voltage to exist across its plate-cathode terminals.

The function of the interconnecting capacitor C1, which shuts off the previously firing gas tube when the second tube begins to fire, is preferably supplemented by two capacitors C4 and C5, which are connected in shunt across the respective cathode-resistors R4 and R5 of the two gas tubes G1 and G2. The effect of these shunting-capacitors C4 and C5 is to short-circuit the associated cathode-resistor, R4 or R5, at the first instant of firing of the associated gas-tube, G1 or G2, as the case may be, thus momentarily bringing the anode-potential of the newly fired tube to a value which is more negative than the steady-state anode-potential of the tube which was previously firing.

The interconnecting capacitor C1, previous to the firing of the newly fired tube, was charged in such polarity as to momentarily tend to hold the anode-potential of the previously firing tube more negative than the anode-potential of the newly fired tube.

The combined effect of the three capacitors C1, C4 and C5 is to strongly depress the anode-potential of the tube which was firing, at the first instant of firing of the second tube, making the anode-potential of the first tube momentarily more negative than its cathode-potential, thus extinguishing the tube. At the same time, the shunting-capacitor C4 or C5, as the case may be, of the tube that is being extinguished, momentarily holds up its cathode-potential to a

value close to the value which it had when the tube was firing, thus assisting in maintaining the reversed tube-voltage for the instant necessary to extinguish the tube.

As explained in the aforesaid Mehring et al. application, the voltage-drops across the two cathode-resistors R4 and R5 are utilized to produce two different effects. The voltage-drop across the cathode-resistor R4 of the first gas tube G1 is utilized to produce half-cycle impulses of square-topped positive voltages for supplying a plate-voltage which is sufficient for initiating and maintaining the operation of an oscillator-tube OSC of a carrier-current transmitter, by connecting the plate-circuit 34 of the oscillator-tube OSC, through a radio-frequency choke RFC, to the cathode-circuit 26 of the first gas tube G1, the cathode of the oscillator being connected, at 35, to the negative battery-terminal (-). The voltage-drop across the cathode-resistor R5 of the second gas tube G2 is utilized to apply an operating voltage-component from the cathode-circuit 27 of the second tube G2 to the grid-circuit 36 of a relay-tube RT, which is shown near the bottom of Fig. 1, and which will be subsequently described. A voltage-drop resistor R-15 is included in the connection between the cathode-circuit 27 of the second trigger-tube G2 and the grid-circuit 36 of the relay-tube RT.

The transmitter-oscillator OSC has a grid-circuit 43 which is connected to the cathode-circuit 35 of said oscillator through a grid-leak resistor GL.

The anode-circuit 34 of the transmitter-oscillator OSC is coupled, by means of a blocking capacitor BC2, to a conductor 49, which constitutes one junction-point of a tuned circuit which includes the conductor 49, a capacitor C6, the cathode-terminal 35, a capacitor C7, the grid-terminal 43, and a variometer V1, and thence back to the conductor 49. The conductor 49 and the grid-terminal 43 are respectively connected to the grid-terminals 44 and 45 of two amplifier-tubes A1 and A2 by means of blocking capacitors BC3 and BC4, respectively.

The amplifier tubes A1 and A2 have a common cathode-circuit 50, which is connected to the conductor 35, and hence the negative battery-terminal (-), through a cathode-resistor R8. The grid-terminals 44 and 45 of the amplifier-tubes A1 and A2 are respectively connected to the negative battery-terminal (-) through resistors R-11 and R-12. The amplifier-tubes A1 and A2 have plate-circuits 51 and 52, respectively, which are connected to the primary-winding terminals of a coupling-transformer 53. The primary-winding mid-point 54 of this coupling-transformer is connected to the positive battery-terminal (+), and it is also connected, through a blocking capacitor BC5, to the cathode-terminal 50 of the amplifier-tubes.

One secondary-winding terminal of the coupling-transformer 53 is grounded, at 57. Another tap-point 58 thereof is connected to a variometer V2, and thence, through a coupling capacitor C-16, to one of the line-conductors of the protected line-section, in a manner which is well-known and needs no further description.

The secondary winding of the coupling-transformer 53 is also provided with another tap-point 60, which is connected to one terminal of the primary winding of a receiver-coupling transformer 62, the other primary-winding terminal of which is connected, through a variable capacitor C-11, to the grounded point 57. The primary winding

of the receiver-coupling transformer 62 is also usually shunted by a voltage-limiting gas tube 64.

The receiver-coupling transformer 62 has a secondary winding, one terminal of which is connected to the grid-circuit 66 of a detector-tube or receiver-tube REC, while the other secondary-winding terminal is connected to the negative battery-terminal (-). The secondary winding of the receiver-coupling transformer 62 is also shunted by a variable capacitor C-12, in a manner which is usual in the art.

The receiver-tube REC is provided with a cathode-circuit 69 which is illustrated as being connected to a tap-point near the negative end of a potentiometer 70 which is energized from the positive and negative buses (+) and (-). This tube also has an anode-circuit 71, which is connected to the positive battery-terminal (+), through a radio-frequency choke RFC'.

The plate or anode-circuit 71 of the receiver-tube REC is also coupled, by means of a capacitor C-13, to a point 74 which is connected to the cathode-circuit 27 of the second tube G2 through a large, capacitor-charging resistor R-14. The point 74 is also connected, through a capacitor C-14, to a conductor 75 which is connected to the cathode-terminal 76 of the lower diode of a double-wave rectifier-valve RV. The plate-circuit of this lower diode is connected to the grid-terminal 36 of the relay-tube RT and to the voltage-drop or load-resistor R-15. The other terminal of the load-resistor R-15 is connected to the cathode-circuit conductor 27 of the second gas triode G2, as previously described. The upper diode-circuit 71 of the double-wave rectifier-valve RV is connected, in the reverse polarity, between the circuits 27 and 75. The load-resistor R-15 is shunted by a radio-frequency by-pass capacitor BPC.

The relay-tube RT is provided with a cathode-circuit 80 which is connected to an intermediate point of a potentiometer 81 which is energized across the battery-terminals (-) and (+). The relay-tube RT is also provided with a plate-circuit 82, which is connected to the positive battery-terminal (+), through the primary winding of a relay-coupling transformer 84, the secondary of which is connected, through a rectifier-bridge 86, to the operating coil R of a tripping-relay R. The relay R is provided with a make-contact 87, which is shown near the top of Fig. 1, in series with the trip-coil TC of the circuit-breaker 16. The output of the rectifier-bridge 86 may be smoothed, if desired, by means of a filter-capacitor FC2.

The fault-detector FD is provided with a make-contact 88, which is connected in the tripping circuit of the circuit-breaker 16, said tripping circuit being traceable from the negative battery-terminal (-), through the fault-detector make-contact 88, and the tripping-relay make-contact R, to the trip-coil TC, and thence through the breaker-switch 16a to the positive battery terminal (+).

The operation of the apparatus shown in Fig. 1 may best be explained with reference to the curve-diagrams of Figs. 2 to 13. The positive-sequence output-terminals I₁ of the filter 18 in Fig. 1, with their associated saturating transformer T₁ and voltage-limiting gas tube 19, produce a single-phase, positive-sequence-responsive output-voltage, one part of which appears across the conductors 24 and 25. This positive-sequence-responsive output-voltage is preferably, as indicated in Fig. 2, a substantially sinusoidal single-

phase wave which has an approximately constant limiting magnitude, for all except the smallest of fault-currents, and which has a phase-angle which is determined by the positive phase-sequence component of the polyphase line-current at the relaying station.

It is usually desirable to transmit carrier-current energy, for protective relaying purposes, only during times of a fault somewhere on the transmission system, and hence it is desirable to utilize some sort of fault-detector. My previously described fault-detector FD is intended to be representative of a detector of this sort. When this fault-detector FD responds, it picks up its make-contacts 32 and 88. The make-contact 32 applies the direct-current battery-voltage to the plate-cathode circuits of the two gas triodes G1 and G2, thus supervising the response to the positive-sequence transformer T₁. The make-contact 88 supervises the tripping circuit.

At a very early stage in each positive half-cycle, the positive-sequence-responsive filter-output of Fig. 2 overcomes the negative bias of the C-battery Ec, or at least it makes the grid-circuit 24 sufficiently positive so that the gas triode G2 fires, and produces a positive voltage-impulse, which is obtained across the cathode-resistor R₅, and comprises the voltage from the negative battery-terminal (-) to the conductor 27 in Fig. 1, as shown in Fig. 3. This is called the operating voltage, because it is a voltage which tends to make the grid-terminal 36 of the relay-tube RT positive with respect to the cathode-circuit 80 of this tube, thus tending to cause current to flow in the plate-circuit 82 of the tube. Since the gas triode G2 is energized from battery-terminals (-) and (+) having a fixed voltage between them, and since the plate-cathode circuits 30-27 of this triode are in series with fixed resistors R₇ and R₅, the positive voltage-impulses which make up the operating voltage are square-topped, and of a substantially constant magnitude, quite irrespective of the magnitude or the wave-form of the positive-sequence-responsive filter-output I₁.

A disadvantage which has heretofore stood in the way of utilizing a positive-sequence current-response in the protection against line-faults has been the very extreme variations which are obtained in the magnitude of the positive-sequence current-component under different fault-conditions, ranging from a very large positive-sequence current, in case of a three-phase fault, to a positive-sequence current which may be many times lower than the maximum power-load current in the case of a single line-to-ground fault of high impedance. This condition is aggravated at a line-terminal which has no source of positive-sequence energy, so that only positive-sequence component of the fault-current is that which is contributed by the rotating electric machines which are connected to that terminal of the line. It is for this reason that I prefer to provide the previously described zero-sequence resistor R₄, or some equivalent means for in any manner increasing the sensitivity of the response of the gas triodes G1 and G2 to the positive-sequence line-current component. In its generic aspects, my invention relates to any means for accomplishing this sensitivity-increasing purpose in the event of a ground-fault. A preferred form of embodiment of such a means is shown in Fig. 1, which is to be taken as illustrative, also, of the generic idea.

In the illustrated form of my invention, as

shown in Fig. 1, the zero-sequence resistor R_1 is connected in series with the C-battery E_C , in a polarity opposite to that of the C-battery. The negative bias or voltage of the C-battery E_C is preferably made abnormally large, or larger than is just barely necessary to prevent excitation of the gas tubes G_1 and G_2 when no single-phase control-voltage is applied across the transformer-terminals 23 and 24, which also constitute the grid-terminals of the respective gas tubes G_1 and G_2 . In the event of a phase-fault, involving two or more of the line-conductors 14, the positive-sequence current-component will be large enough to saturate the positive-sequence transformer T_1 , and large enough to exceed the setting of the voltage-limiting gas tube 18, so as to produce a fixed constant magnitude of single-phase voltage which is sufficient to cause the respective gas triodes G_1 and G_2 to become conducting at an early part of alternate half-cycles of the voltage-supply, as previously explained.

In the event, however, of a single line-to-ground fault through a very high impedance, such as would be obtained by a broken line-conductor lying upon dry or frozen ground, the positive-sequence voltage component or output of the transformer T_1 might not be large enough to satisfactorily control the gas triodes G_1 and G_2 . In such a case, however, a zero-sequence current-component will be present, which energizes the zero-sequence transformer T_0 to saturation, and the output of this transformer is rectified and applied to the load-resistor R_1 in such polarity as to produce a voltage-drop or potential opposite to the potential of the grid-biasing battery E_C , but preferably having a limited magnitude such that the zero-sequence-responsive unidirectional voltage will not of itself suffice to cause the gas triodes G_1 and G_2 to begin to transmit plate-cathode current in the absence of any positive-sequence-responsive single-phase control-voltage across the terminals 23 and 24.

The zero-sequence resistor R_1 nevertheless neutralizes some or all of the C-battery voltage E_C , as indicated at 22 in Fig. 1. Thus it predisposes the grids of both of the gas triodes G_1 and G_2 to be ready to make the tubes conductive when their respective grids are made just a little bit more positive with respect to their tube-cathodes, as by the application of a relatively small alternating voltage, applied across the grid-terminals 23 and 24, from the positive-sequence transformer T_1 .

At a very early period in each negative half-cycle of the filter-output which is shown in Fig. 2, the other gas triode G_1 of Fig. 1 fires, immediately extinguishing the previously firing triode G_2 , in a manner which has previously been described. The operation of this other gas triode G_1 produces a succession of positive voltage-impulses which alternate with the positive impulses which constitute the operating voltage of Fig. 3. The positive voltage-impulses of this other triode G_1 are obtained across the cathode-resistor R_4 , in the form of a positive voltage which appears between the negative battery-terminal (--) and the conductor 26, which is connected to the plate-circuit 34 of the transmitter-oscillator OSC, through the radio-frequency choke RFC of Fig. 1. This causes the oscillator OSC to immediately begin oscillating, thus initiating the transmission of carrier. The transmission of carrier continues, at approximately its full, constant strength, as long as the gas triode G_1 is firing, which is to say, during the negative half-cycles

of the filter-output of Fig. 2, as shown diagrammatically in Fig. 4.

In Fig. 4, the frequency of the carrier-current waves cannot be shown to scale, because the carrier-current frequency is actually so high that it would not begin to be shown in the space which we have allotted to Fig. 4.

After the first impulse of carrier-current transmission, during the first negative half-cycle of the positive-sequence filter-output after the response of the fault-detector FD, the first-mentioned gas triode G_2 again becomes conducting, extinguishing the triode G_1 , and thus interrupting the carrier-current transmission for a half-cycle period, corresponding to the next positive half-cycle of the positive-sequence filter-output.

It will be noted that the action just described occurs at both terminals of the protected line-section 14, or at all of the terminals, in case the protected line-section has more than two terminals. It will be noted that the equipment at each terminal responds to the positive-sequence component of the line-current input into the protected line-section at its own terminal, that is, from the bus 15 at that terminal. In the event of an internal fault, that is, a fault within the confines of the protected line-section, the positive-sequence component of the fault-current will be flowing into the line-section at each terminal thereof, and these fault-currents will be more or less in phase with each other, because the positive-sequence terminal-voltages of the line are not greatly out of phase with each other, while the line-impedance which limits the fault-current from each terminal to the fault-location has approximately the same impedance-angle in each case. For an internal fault, therefore, it may be assumed, as a first approximation, that the positive-sequence fault-current components are in phase with each other at both or each of the line-terminals. This is depicted in Fig. 5, which shows that the distant carrier, which is transmitted at another line-terminal other than the illustrated line-terminal, is transmitted at the same time as the local carrier which is shown in Fig. 4, for an internal fault, that is, out of phase with the operating impulses of Fig. 3.

In the event of an external fault, however, positive-sequence current will be flowing out of the line-terminal which is closest to the external fault, and it will be flowing into the protected line-section at at least one other terminal. Since each terminal equipment responds to a positive-sequence current-direction looking into the protected line-section at that terminal, the line-current at the terminal closest to the external fault will be reversed, approximately 180° in the ideal case, with respect to the current in some other terminal. Hence, at each terminal, local carrier will be transmitted at certain half-cycles of the line-frequency, as shown in Fig. 4, and distant carrier will be transmitted at some distant terminal during line-frequency half-cycles which are displaced approximately 180° (in the ideal case) with respect to the line-frequency half-cycles of the local carrier. Fig. 6 depicts the distant carrier-current transmission for an external fault.

In the operation of the particular system shown in Fig. 1, it will be noted that carrier-current energy, from both the local and distant transmitters, is received by the receiver-tube REC, so as to produce a plate-cathode current through this tube during periods when the carrier-current energy is being received.

When no carrier-current energy is being re-

ceived, the anode-terminal 71 of the receiver-tube REC is practically at the potential of the positive battery-terminal (+), and hence the capacitor C-13 is charged in accordance with the potential-difference between said anode-terminal 71 of the receiver and the cathode-terminal conductor 27 of the second gas triode G2, the receiver-connected terminal of the capacitor C-13 being positive. The conductor 27 has a potential such as is depicted in Fig. 3, varying between zero, which is taken as the potential of the negative battery-terminal (-), and a fraction of the total battery-voltage, which is utilized as the operating-voltage for the grid-circuit 36 of the relay-tube RT, this operating-voltage being the voltage-drop of the cathode-resistor R5 of the second gas triode G2, whenever the latter is firing.

When the carrier-current energy is received, the receiver-tube REC becomes conducting, pulling down the potential of its anode-terminal 71 to a point which is more or less close to the potential of the negative battery-terminal (-), thus more or less short-circuiting the capacitor C-13, and causing it to discharge, drawing current through the load-resistor R-15 and the lower diode of the rectifier-valve RV, said diode being connected in such polarity as to permit current-flow in the direction from the conductor 27 to the conductor 36, and thence through the lower diode to the conductor 76 and the capacitors C-14 and C-13. At the same time, a much smaller current flows through the much larger capacitor-charging resistance R-14, which is utilized to charge the capacitor C-13.

During the periods when no carrier-current energy is being received, in the illustrated form of embodiment of my invention, the receiver-plate-circuit 71 again becomes quite positive, so that the upper diode-circuit 77 of the rectifier-valve RV becomes conducting and charges the capacitor C-14, making the terminal 74 positive and the terminal 75 negative, thus causing the capacitor C-14 to act as a voltage-doubler for doubling the effective voltage of the capacitor C-13.

When, therefore, carrier-current energy is again received, on the next half-cycle of the line-frequency current, the two capacitors C-14 and C-13 discharge through the load-resistor R-15, thus producing a negative or restraining voltage-drop in said load resistor R-15, making the conductor 36, and hence the grid of the relay tube RT, negative with respect to the potential of the cathode-circuit conductor 27 of the second tube G2. The reception of carrier-current thus causes the capacitors C-14 and C-13 to discharge, producing a voltage-drop in the load-resistor R-15, making the grid of the relay-tube RT more negative, and thus effectually preventing this tube from operating in response to the operating-voltage which is produced by the current-flow in the cathode-resistor R5 of the second gas tube G2.

The radio-frequency or carrier frequency component of the plate-voltage of the receiver-tube REC is by-passed from the load-resistor R-15 by the by-passing capacitor BPC.

Fig. 7 shows the negative or restraining voltage, across the resistor R-15, for an internal fault in which the positive-sequence components of the fault-currents are in phase with each other at both or all of the line-terminals, while Fig. 8 shows the corresponding restraining voltage for an external fault in which the outwardly flowing positive-sequence current at one line-

5

terminal is exactly 180° out of phase with the inwardly flowing positive-sequence current or currents at the other terminal or terminals of the protected line section.

The receiver-tube REC preferably has a constant-current characteristic, so that whenever its grid permits plate-current to flow, the plate-current will have an approximately constant value. Thus, as shown in Fig. 8, the half-cycles of receiver plate-current, during which carrier-current energy is being received by the receiver-tube REC from the distant carrier, transmitted from some other line-terminal, are of an approximately fixed magnitude, regardless of carrier-current attenuation. Hence the restraining voltage-impulses in the resistor R-15 are of an approximately fixed magnitude. The receiver plate-current impulses which are received from the distant carrier are of approximately the same magnitude as the half-cycle impulses of plate-current which are produced when carrier-current energy is being received from the local transmitter, even though the local signals may be the stronger.

It is preferable, also, that the relay-tube RT shall have a constant-current characteristic, so that its plate-current will be constant, as shown in Fig. 11, without sensitive dependence upon the precise magnitude of its grid-voltage. Thus, the exact amount of the restraining voltage, produced by the receipt of carrier-current energy, as shown in Fig. 8, is not important, so long as said restraining voltage is greater than the operating voltage of Fig. 3, or the voltage-drop in the resistor R5, by a safe margin.

It is further to be noted that the only carrier-current response of any moment is the response to the distant carrier, that is, the carrier-current impulses which are transmitted from some other line-terminal or terminals. The carrier-current energy received from the local carrier-current transmitter is immaterial, because, by the very nature of the control, it is always transmitted (and received) during the half-cycles alternating between the half-cycles when the operating impulses of Fig. 3 are present.

The grid-voltage of the relay-tube RT is thus made up of three components: First, there is a negative grid-bias consisting of the voltage between the potentiometer-tap 89 and the negative battery-terminal, which is sufficient to bias the grid of the relay-tube RT so that no plate-current flows in said tube when there is no restraining or operating voltage present. A second component of the grid-voltage of the relay-tube RT is the operating voltage, in the form of positive voltage-impulses produced whenever the cathode-circuit current of the second gas tube G2 flows through the cathode-resistor R5, as shown in Fig. 3. The third grid-voltage component of the relay-tube RT is the restraining voltage, in the form of negative voltage-impulses as shown in Figs. 7 and 8, for an internal fault and an external fault, respectively. This restraining voltage is produced by the discharge of the capacitors C-14 and C-13 through the resistor R-15 whenever carrier-current energy is being received, although the restraining impulses which are received from a distant line-terminal are the only ones of importance. The resultant grid-voltage of the relay-tube RT is shown in Figs. 9 and 10, for an internal fault and an external fault, respectively.

Since the relay-tube RT will be operated, or carry a plate-current, only when its grid is sufficiently positive with respect to its cathode, a

plate-current will flow in the relay-tube RT only during the positive-half-cycles of the grid-voltages shown in Figs. 9 and 10, that is, only when the local operating impulses of the second-valve cathode-circuit conductor 27 and its cathode-resistor R5 are not opposed by the restraining impulses received from a distant line-terminal.

When there is an internal fault, accompanied by fault-currents which are in phase with each other at the several line-terminals, the plate-current of the relay-tube RT takes the form of a succession of square-topped half-cycles corresponding in timing to the line-frequency half-cycles when the second gas tube G2 is firing, as depicted in Fig. 11, thus energizing the local tripping-relay R and causing a local tripping-operation. In the case of an external fault, with line-currents exactly 180° out of phase with each other, the grid-biasing voltage of the relay-tube RT is entirely negative, as shown in Fig. 10, and the plate-current of the relay-tube RT is zero, as shown in Fig. 12, meaning no response of the relay R, and hence no tripping-operation.

While I have discussed the ideal cases of an internal fault in which there is a 0° phase-angle between the terminal positive-sequence line-current components, and an external fault in which there is a 180° phase-displacement, counting inwardly flowing currents as positive, or in phase with each other, at each terminal, it is to be noted that, in actual cases, the terminal positive-sequence line-current components for internal faults will not, in general, be exactly in phase with each other, but will vary in phase, by a certain amount, so that the impulses of the plate-current of the relay-tube will be shorter than the half-cycle impulses shown in Fig. 11, depending upon the phase-angle, because the operating impulses of Fig. 3 will be partially overlapped or blocked by received impulses from the distant transmitter, according to the phase-angle between the positive-sequence fault-current components at the different stations.

Fig. 13 shows a plot of the integrated, or root-means-square, or averaged, current in the relay-coil R, in milliamperes, plotted against the phase-angle of the terminal line-currents. It shows that, as the phase-angle departs from zero, in either the leading direction or the lagging direction, the relay-current falls off, or becomes smaller and smaller, until the phase-angle becomes 180°. The tripping-relay R is really an overcurrent relay, and it is adjusted to have a pick-up value 99 (Fig. 13) which permits the internal-fault currents at the several terminals to be out of phase with each other as much as 120°, while still permitting the fault-responsive tripping-relay R to pick up. This leaves the phase-angles between 120° and 180° to represent external-fault conditions, during which the relay R does not pick up. It will be understood, of course, that the pick-up value of the relay-current can be set for any desired magnitude, corresponding to any desired phase-angle between the terminal line-currents, in accordance with the necessities of special conditions existing on any particular line.

The relay-tube RT preferably has a constant-current characteristic, so that whenever its grid permits plate-current to flow, the plate-current will have an approximately constant value, as shown in Fig. 11, without sensitive dependence upon the precise magnitude of the grid-voltage. Hence, the integrated, or root-mean-square, or average, value of the plate-current will depend

only upon the relative lengths of the time-periods during which the plate-current is flowing, as shown in Fig. 13.

Since the relay-current is measured in milliamperes, it is usually more convenient to utilize a sensitive polarized relay R, or other sensitive direct-current relay R, to respond to this plate-current, rather than utilizing an alternating-current relay for this purpose. For this reason, I have provided the plate-circuit transformer 84, and the rectifier-bridge 86, so that I may utilize a sensitive direct-current milliamperes-relay R, as shown in Fig. 1.

The relay R, as previously described, has a make-contact 87 in the tripping-circuit of the breaker 16, so that, whenever the relay R picks up, the circuit-breaker 16 is tripped. Because of the sensitive nature of the relay R, and the possibility of shock-excitation of the carrier-current receiver-circuits due to static conditions, or the like, it is usually desirable to safeguard the tripping-circuit by providing some additional fault-responsive contact, in addition to the contact 87 of the relay R, and I have provided for this, in Fig. 1, by means of the contact 88 of the fault-detector FD, which is intended to be representative of any fault-detector contact which is controlled independently of the carrier-current channel, and which is intended merely to make sure that there is a fault somewhere on the transmission system, before a tripping operation is permitted in response to the receiver-relay contact R.

Since my illustrated system utilizes only one fault-detector, which is shown at FD, it is necessary to guard against erroneous relay-operation in the event of a distant fault which might cause a picking up of the fault-detector at only one end of the protected line-section. To eliminate the possibility of incorrect relaying under these conditions, I prefer to arrange the circuit-constants so that the gas triode G1, which controls carrier, fires at a lower voltage of the filter output-circuit 23, 24 than the gas triode G2 which provides operating voltage to the grid-circuit 36 of the relay-tube RT.

The gas triode G1 which controls carrier fires preferably immediately upon the closure of the contact 32 of the detector FD. The second gas triode G2 fires at a grid-voltage which is sufficiently above the pick-up voltage of the detector FD to insure that the fault-detectors FD at both ends of the line-section will pick up before the second gas triode G2 applies an operating voltage to the relay-tube RT at either end of the line. Consequently, if only one fault-detector picks up, at only one end of the line, there will not be enough control-voltage across 23 and 24 to cause the diode G2 to fire at either end of the line, and hence the relay-tube RT cannot carry current to operate the tripping-relay R at either end of the line.

In Fig. 1, the resistor R2 is illustrated as being larger than R3, so that, with identical tubes G1 and G2, the tube G1 will receive the larger portion of the voltage across 23 and 24. The tube G2 may fire at a voltage which is 20% to 50% above the control-voltage (across 23 and 24) which results in the firing of the tube G1.

It will be observed that I obtain phase-angle comparison of the line-currents at different terminals of a protected line-section by utilizing the positive-sequence components of the line-currents at the respective line-terminals as phase-angle control-means, for providing, at each ter-

5
minal, a succession of flat-topped constant-magnitude positive operating-impulses which are effective locally, and, alternating therewith, a succession of flat-topped constant-magnitude negative restraining-impulses which are received from the other line-terminal or terminals. I also supervise this positive-sequence response with a multi-responsive fault-detector means, preferably in the form of a single voltage E_{10} which is a composite of various phase-sequence components or phases of the line-current. I further increase the sensitivity of my response to the positive-sequence components of ground-fault currents, by means of a ground-fault detector, preferably a ground-fault detector which responds to ground faults by producing a constant-magnitude unidirectional voltage of substantially non-pulsatory form.

10
I have also provided a novel control-circuit in which a constant-magnitude unidirectional voltage is added to a single-phase positive-sequence-responsive voltage whenever there is a ground-fault on the system. I have also made use of such a combination of a direct-current voltage added to an alternating-current voltage, in a gas tube $G1$ or $G2$, each of which is representative of any polarity-responsive device which is responsive to the voltage half-waves of only one polarity.

15
While I have illustrated my invention in but a single form of embodiment, which I at present prefer, I desire it to be understood that such illustration is only illustrative, and that various changes of omission and addition and substitution may be made without departing from many of the essential features of my invention, as will be well understood by those skilled in the art. I desire, therefore, that the appended claims shall be accorded the broadest construction consistent with their language.

20
I claim as my invention:

25
1. Terminal equipment for one terminal of a pilot-channel phase-angle-detecting relaying-system adapted to protect a section of a three-phase transmission-line against faults, comprising means operative to develop a single-phase voltage having a phase which is responsive substantially solely to the positive-sequence component of the line-current at said terminal, local control-means operative to develop a succession of operating impulses in response to positive half-cycles of said voltage, pilot-channel means operative to transmit a succession of restraining impulses and to make them effective at another line-terminal or terminals in response to negative half-cycles of said voltage, and phase-angle-detecting relay-means operative to respond to said operating impulses when they are not effectively opposed by restraining impulses received from a distant line-terminal.

30
2. The invention as defined in claim 1, in combination with multi-responsive fault-detector means, responsive to line-conditions at said terminal, for detecting the existence of any one of a plurality of different kinds and phases of ground- and phase-faults with uncertainty as to whether the fault is inside of or outside of the protected line-section, and means for supervising the operation of said phase-angle-detecting relay-means in response to a fault-indication by said fault-detector means.

35
3. The invention as defined in claim 1, in combination with multi-responsive fault-detector means, responsive to line-conditions at said terminal, for detecting the existence of any one

40
of a plurality of different kinds and phases of ground- and phase-faults with uncertainty as to whether the fault is inside of or outside of the protected line-section, and means for causing said local control-means and said pilot-channel means to be effectively operative only when there is a fault-indication by said fault-detector means.

45
4. The invention as defined in claim 1, in combination with ground-fault detector-means, responsive to line-conditions at said terminal, for increasing the effectiveness of said single-phase voltage in the event of a predetermined ground-fault condition.

50
5. Multi-responsive fault-detector means, adapted to be responsive to a plurality of different kinds and phases of ground- and phase-faults on a three-phase line, comprising positive-sequence means operative to develop a voltage which is substantially solely responsive to the positive-sequence component of the line-current, means responsive to said voltage, and ground-fault detector-means, responsive to line-conditions, for increasing the effectiveness of said voltage in the event of a predetermined ground-fault condition.

55
6. Multi-responsive fault-detector means, adapted to be responsive to a plurality of different kinds and phases of ground- and phase-faults on a three-phase line, comprising positive-sequence means operative to develop a voltage which is substantially solely responsive to the positive-sequence component of the line-current, a tube, means for causing said tube to operate in response to said voltage, and means for increasing the sensitivity of tube-response to said voltage in response to a predetermined ground-fault condition on the line.

60
7. Multi-responsive fault-detector means, adapted to be responsive to a plurality of different kinds and phases of ground- and phase-faults on a three-phase line, comprising means operative to develop a pulsating voltage having a phase which is responsive substantially solely to the positive-sequence component of the line-current, ground-fault detector-means operative to develop a ground-fault-responsive voltage-component of a limited magnitude and a unidirectional form in the event of a predetermined ground-fault condition on the line, and circuit-means for combining said voltage-components in series.

65
8. Multi-responsive fault-detector means, adapted to be responsive to a plurality of different kinds and phases of ground- and phase-faults on a three-phase line, comprising means operative to develop a pulsating voltage having a phase which is responsive substantially solely to the positive-sequence component of the line-current, ground-fault detector-means, responsive to line-conditions, for developing a uni-directional voltage of substantially non-pulsatory form in the event of a predetermined ground-fault condition, a polarity-responsive device, means for causing said device to be operatively conducting on alternate half-cycles of the line-current frequency in response to said pulsating voltage, and means, responsive to said substantially non-pulsatory voltage, for increasing the sensitivity of the aforesaid response to the pulsating voltage.

70
9. Multi-responsive fault-detector means, adapted to be responsive to a plurality of different kinds and phases of ground- and phase-faults on a three-phase line, comprising a tube, means for normally providing a tube-circuit voltage which prevents the tube from becoming ef-

effectively conductive, ground-fault detector-means, responsive to line-conditions, for at times providing a unidirectional voltage of substantially non-pulsatory form in a circuit of said tube and in the polarity tending to make the tube become effectively conductive, means operative to develop a pulsating voltage having a phase which is responsive substantially solely to the positive-sequence component of the line-current, and means for making said pulsating voltage effective in a circuit of said tube in such manner as to tend to cause the tube to be operatively conductive on alternate half-cycles of the line-current frequency in response to the pulsations of said pulsating voltage.

10. The invention as defined in claim 9, characterized by said non-pulsatory voltage having a limited magnitude which is insufficient to cause any material operative conduction of the tube in the absence of a positive-sequence-responsive pulsating voltage.

11. Multi-responsive fault-detector means, adapted to be responsive to a plurality of different kinds and phases of ground- and phase-faults on a three-phase line, comprising a tube having control-circuit means, a direct-current plate-voltage supply-circuit for said tube, means for normally providing a control-circuit voltage which prevents the tube from becoming effectively conductive, ground-fault detector-means, responsive to line-conditions, for at times providing a unidirectional voltage of substantially non-pulsatory form in a control-circuit means of said tube and in the polarity tending to make the tube become effectively conducting, means operative to develop a pulsating voltage having a phase which is responsive substantially solely to the positive-sequence component of the line-current, and means for making said pulsating voltage effective in a control-circuit means of said tube in such manner as to tend to cause the tube to be operatively conductive on alternate half-cycles of the line-current frequency in response to the pulsations of said pulsating voltage.

12. The invention as defined in claim 11, characterized by said non-pulsatory voltage having a limited magnitude which is insufficient to cause any material operative conduction of the tube in the absence of a positive sequence-responsive pulsating voltage.

13. The invention as defined in claim 9, characterized by said non-pulsatory voltage having a limited magnitude which is insufficient to cause any material operative conduction of the tube in the absence of a single-phase voltage.

14. Terminal equipment for one terminal of a pilot-channel phase-angle-detecting relaying-system adapted to protect a section of a three-phase transmission-line against faults, comprising current-responsive voltage-developing means operative to develop a pulsating voltage having a phase which is responsive to a function of the three-phase line-current at said terminal, ground-fault detector-means for selectively responding to ground-fault line-conditions more sensitively than said current-responsive voltage-developing means, means controlled by said ground-fault detector-means for making said current-responsive voltage-developing means respond more sensitively to said function of the three-phase line-current, local control-means operative to develop a succession of operating impulses in response to positive half-cycles of said pulsating voltage, pilot-channel means operative to transmit a succession of restraining impulses and to make them

effective at another line-terminal or terminals in response to negative half-cycles of said pulsating voltage, and phase-angle-detecting relay-means operative to respond to said operating impulses when they are not effectively opposed by restraining impulses received from a distant line-terminal.

15. Multi-responsive fault - detector means, adapted to be responsive to a plurality of different kinds and phases of ground- and phase-faults on a three-phase line, comprising current-responsive voltage-developing means operative to develop a voltage-component which is responsive to a function of the three-phase line-current, ground-fault detector-means for selectively responding to ground-fault line-conditions more sensitively than said current-responsive voltage-developing means, said ground-fault-detector-means being operative to develop a ground-fault responsive voltage-component of a limited magnitude and a unidirectional form, circuit-means for combining said voltage-components in series, and means responsive to said combined voltage-components.

25 16. Multi-responsive fault-detector means, adapted to be responsive to a plurality of different kinds and phases of ground- and phase-faults on a three-phase line, comprising current-responsive voltage-developing means operative to develop a pulsating voltage-component having a phase which is responsive to a function of the three-phase line-current, ground-fault detector-means for selectively responding to ground-fault line-conditions more sensitively than said current-responsive voltage-developing means, said ground-fault detector-means being operative to develop a unidirectional voltage of substantially non-pulsatory form, a polarity-responsive device, means for causing said device to be operatively 30 conducting on alternate half-cycles of the line-current frequency in response to said pulsating voltage, and means, responsive to said substantially non-pulsatory voltage, for increasing the sensitivity of the aforesaid response to the pulsating voltage.

17. Terminal equipment for one terminal of a pilot-channel phase-angle-detecting relaying-system adapted to protect a section of a three-phase transmission-line against faults, comprising current-responsive voltage-developing means operative to develop a pulsating voltage having a phase which is responsive to a function of the three-phase line-current at said terminal, ground-fault detector-means for selectively responding to 50 ground-fault line-conditions more sensitively than said current-responsive voltage-developing means, said ground-fault detector-means being operative to provide a unidirectional voltage of substantially non-pulsatory form, a tube, means for normally providing a tube-circuit voltage which prevents the tube from becoming effectively conductive, means for making said unidirectional voltage effective in a circuit of said tube in the polarity tending to make the tube 55 become effectively conductive, means for making said pulsating voltage effective in a circuit of said tube in such manner as to tend to cause the tube to be operatively conductive on alternate half-cycles of the line-current frequency in response to the pulsations of said pulsating voltage, local control-means responsive to said tube for developing a succession of operating impulses during alternate half-cycles of said pulsating voltage, pilot-channel means responsive to said tube 60 for transmitting a succession of restraining im-

pulses and making them effective at another line-terminal or terminals during the other half-cycles of said pulsating voltage, and phase-angle-detecting relay-means operative to respond to said operating impulses when they are not effectively opposed by restraining impulses received from a distant line-terminal.

18. Terminal equipment for one terminal of a pilot-channel phase-angle-detecting relaying-system adapted to protect a section of a three-phase transmission-line against faults, comprising current-responsive voltage-developing means operative to develop a single-phase voltage having a phase which is responsive to a function of the three-phase line-current at said terminal, ground-fault detector-means for selectively responding to ground-fault line-conditions more sensitively than said current-responsive voltage-developing means, said ground-fault detector-means being operative to provide a unidirectional voltage of substantially non-pulsatory form, electronic apparatus comprising two tubes, means for making said single-phase voltage effective in circuits of the two tubes in such manner as to tend to cause one tube to be operatively conductive on positive half-cycles of said single-phase voltage and to tend to cause the other tube to be operatively conductive on negative half-cycles of said single-phase voltage, means for making said unidirectional voltage effective in circuits of said tubes in a polarity facilitating the operative conductivity of said tubes, local control-means responsive to the operation of one tube for developing a succession of operating impulses, pilot-channel means responsive to the operation of the other tube for transmitting a succession of restraining impulses and making them effective at another line-terminal or terminals, and phase-angle-detecting relay-means operative to respond to said operating impulses when they are not effectively opposed by restraining impulses received from a distant line-terminal.

19. Terminal equipment for one terminal of a pilot-channel phase-angle-detecting relaying-system adapted to protect a section of a three-phase transmission-line against faults, comprising current-responsive voltage-developing means operative to develop a single-phase voltage having a phase which is responsive to a function of the three-phase line-current at said terminal, ground-fault detector-means for selectively responding to ground-fault line-conditions more sensitively than said current-responsive voltage-developing means, said ground-fault detector-means being operative to provide a unidirectional voltage of substantially non-pulsatory form, electronic apparatus comprising two tubes, each having control-circuit means, supply-leads adapted to provide a direct-current plate-voltage supply-circuit for each tube, means for normally providing each tube with a control-circuit voltage which prevents the tube from becoming effectively conductive, means for making said unidirectional voltage effective in circuits of said tubes in the polarity tending to make the tube become effectively conducting, means for making said single-phase voltage oppositely effective in circuits of the two tubes in such manner as to tend to cause one tube to be operatively conductive on positive half-cycles of said single-phase voltage and to tend to cause the other tube to be operatively conductive on negative half-cycles of said

single-phase voltage, local control-means responsive to the operation of one tube for developing a succession of operating impulses, pilot-channel means responsive to the operation of the other tube for transmitting a succession of restraining impulses and making them effective at another line-terminal or terminals, and phase-angle-detecting relay-means operative to respond to said operating impulses when they are not effectively opposed by restraining impulses received from a distant line-terminal.

20. Terminal equipment for one terminal of a pilot-channel phase-angle-detecting relaying system adapted to protect a section of a three-phase transmission-line against faults, comprising phase-sequence means for developing two different single-phase control-voltages in response to two different phase-sequence functions of the line-current at the relaying terminal, local control-means responsive to a first one of said control-voltages for producing a succession of restraining impulses in response to negative half-cycles of said first control-voltage when said control-voltage exceeds a predetermined magnitude, and for producing a succession of operating impulses in response to positive half-cycles of said first control-voltage when said control-voltage exceeds a predetermined magnitude, means responsive to the second control-voltage for increasing the sensitiveness of the response of said local control-means to said first control-voltage, fault-detector means for responding to locally detectable fault-conditions on the transmission-line, means for utilizing said fault-detector means in controlling said local control-means, pilot-channel means operative to transmit said succession of restraining impulses and to make them effective at another line-terminal or terminals, and phase-angle-detecting relay-means operative to respond to said operating impulses when they are not effectively opposed by restraining impulses received from a distant line-terminal.

21. Terminal equipment for one terminal of a pilot-channel phase-angle-detecting relaying system adapted to protect a section of a three-phase transmission-line against faults, comprising phase-sequence means for developing a single-phase control-voltage in response to a phase-sequence function of the line-current at the relaying terminal, local control-means responsive to said control-voltage for producing a succession of restraining impulses in response to negative half-cycles of said control-voltage when said control-voltage exceeds a predetermined magnitude, and for producing a succession of operating impulses in response to positive half-cycles of said control-voltage when said control-voltage exceeds a predetermined magnitude, fault-detector means for selectively responding to a locally detectable fault-condition other than a balanced three-phase fault on the transmission-line, means for utilizing said fault-detector means to increase the sensitivity of response of said local control-means, pilot-channel means operative to transmit said succession of restraining impulses and to make them effective at another line-terminal or terminals, and phase-angle-detecting relay-means operative to respond to said operating impulses when they are not effectively opposed by restraining impulses received from a distant line-terminal.
